UNITED STATES PATENT OFFICE.

VINCENZO GUARDINO, OF BROOKLYN, NEW YORK.

ICE-CREAM-CUTTING MACHINE.

Application filed March 17, 1922. Serial No. 544,468.

To all whom it may concern:

Be it known that I, VINCENZO GUARDINO, a citizen of the United States, and resident of the city of New York, borough of Brooklyn, county of Kings, and State of New York, have invented a new and Improved Ice-Cream-Cutting Machine, of which the following is a full, clear, and exact description.

10 My invention relates to a cutting machine, and aims to provide a device of this nature particularly adapted for use with the cutting of ice cream or a similar substance, the present invention being intended to provide 15 certain improvements over my prior U. S. Patent No. 1,434,888, granted November 7, 1922.

It is an object of the present invention to provide a device of the character stated 20 in which feeding mechanism will form a part of the machine, the said feeding mechanism being actuated in an improved and positive manner to insure the achievement of the result desired.

25 It is a further object of this invention to provide a cutting element operating in connection with the feeding mechanism which cutting element will have a stripping mechanism associated with it, whereby any tendency of the material being cut, clinging to the knife will be avoided.

30 My invention further contemplates the provision of a structure by means of which the feeding mechanism will be cleansed after each operation, thereby insuring a standard 35 of sanitation which will be far above that achieved by machines of a similar type.

A still further object of this invention is 40 that of providing a knife mechanism by means of which the ice cream or similar substance may be divided transversely, longitudinally and from the sides, and

45 Still further objects of this invention will become apparent in the annexed specification taken in connection with the drawings, which latter illustrate one practical embodiment of the same, and in which:

Figure 1 is a plan view of a cutting machine embodying my improved construction.

50 Figure 2 is a side elevation thereof with certain of the parts broken away to disclose underlying construction.

Figure 3 is a transverse sectional end view of the machine.

55 Figure 4 is an enlarged fragmentary sectional view of a detail of construction.

Figure 5 is a sectional plan view taken along the line 5—5 and in the direction of the arrows indicated in Figure 6, and

Figure 6 is an end view of the parts illustrated in Figure 5, it being noted that these two latter figures disclose in detail the construction of a cutting apparatus which may be utilized in conjunction with the machine.

As has been shown in these various figures, the reference numeral 10 indicates a table or platform which may be suitably supported by a frame 11, it being noted in this connection that an opening is provided extending centrally of the table, which opening is formed with rail portions 12 adjacent its edges for a purpose hereinafter specified.

Any suitable type of conveyor may be utilized to effect a feeding of the substance 75 along the table, but in the embodiment illustrated it will be seen that I have provided sprocket wheels 13 adjacent each end of the opening of the table, and an endless sprocket chain 14 extends around these wheels so 80 that when the latter are rotated the chain will be bodily moved. Affixed to certain links of the chain are platforms 15 which in aggregate when arranged in a common plane provide a continuous surface, and the 85 rail portions 12 forming a part of the table serve as rests for these platforms, as well as guides for the same, so that a continuous even moving surface fills the opening forming a part of the table.

90 It will thus be obvious, assuming that suitable mechanism is provided to move the chain, that the conveyor thus formed will be moved continuously along the table, and thus any substance placed upon the conveyor will also be moved along the table. In view of the fact that the machine is particularly intended for the handling of ice cream and similar substances, I affix 95 gripping or contact shoes 16 one to each of the platforms 15, and thus it will be obvious that irrespective of the operations which the material undergoes, in its passage along the table, these operations will not effect a movement of the material or substance with 100 respect to the platform.

Now with a view of providing mechanism which will serve to positively move the conveyor, attention is primarily invited to Figures 2 and 3, it will be seen in these 110 views that one of the sprocket wheels is mounted upon a shaft 17 to which a ratchet

18 is attached, it being also noted that a beam 19 is mounted upon this shaft in such a manner that it is capable of being oscillated. A main operating shaft 20 is carried by the frame 11 and mounts eccentrics 21, one of which may carry a roller 22, and a lever 23 carries near one of its ends a rigidifying enlargement 23^a adapted at intervals to be engaged by a roller 22 and 10 lifted above shaft 20 against the action of a spring 24. The opposite end of this lever 23 is connected to the beam 19 by means of a link 25. A movable fulcrum for the lever 23 is provided by rockingly securing 15 the same to a traveler 26 which may be positively moved by any suitable means such as a screw threaded shaft 27 conveniently operated by a hand crank 28. The parts just described permit careful adjustment of 20 the lever 23 in setting up the machine.

Thus it will be appreciated that the rotation of the shaft 20 will result in the eccentric 21 also being rotated, and incident to the fact that the lever 23 is urged 25 toward the roller 22 by means of the spring 24 it will be obvious that the said lever will be intermittently rocked. This motion will be transmitted to the link 25 and in turn to the beam 19, and due to the fact that the 30 beam carries a pawl 29 which is in engagement with the ratchet 18 it will be seen that the rocking of the lever will be translated into rotation on the part of the shaft 17. No spring of the common leaf or coil wire 35 type is shown in connection with the pawl 29, although, of course, the use of such spring may be made. I prefer to design the pawl as indicated so that the same is suitably proportioned and disposed to locate 40 its main weight-masses above its point of pivoting and lying to one side of such point and in toward the ratchet.

After the substance to be cut has been moved by the conveyor to the end of the 45 table it may be moved to a delivery platform by any suitable means such as a chute 30, which will deliver the substance to a second conveyor 21 associated with the delivery table 32. However to cleanse the 50 platform of the first named conveyor after it has effected its delivery it will be seen, reference being had to Figure 3 that a trough 33 extends below the opening within the table 11 and the platforms upon their 55 return passage to the forward end of the table, pass between two perforated pipes 34, which latter straddle the conveyor and serve to direct jets of fluid against the opposite faces of the platform to accomplish the 60 result desired, the waste fluid flowing from the trough 33 through a suitable drain pipe 35.

The eccentrics 21 in addition to effecting a movement of the conveyor, also serve to 65 operate the cutting knife 36, and this lat-

ter member is preferably carried by a head 37 slidably carried upon columns 38 secured to the table. Crank arms 39 have one of their ends attached to the head 37 and their opposite ends terminate in bearings 40 encircling the eccentrics 21. Thus while the lever 23 has its link-adjacent end swinging upwardly and lost motion is occurring between the pawl and ratchet structure, and the conveyor is accordingly remaining stationary, the eccentrics will effect a depression of the head by means of the crank arms 39, and the knife 36 will be depressed to effect a severance of the substance upon the conveyor.

Assuming that ice cream or a similar substance is being cut into blocks by the machine, it will be appreciated that under certain conditions this substance will tend to cling to the knife blade upon the latter being retracted by the continued rotation of the eccentrics, and with a view of preventing this occurring, I provide stripping means serving to effect a detachment of the substance from the knife. In the embodiment illustrated this stripping means includes standards 41 which carry spring pressed rods 42 in turn supporting blades 43. These latter elements are arranged in a plane just beyond the plane normally occupied by the upper surface of the substance being cut, which is thus free to move under the same. Upon this substance being carried upwardly by the knife, however, it will be obvious that the upper surface of the same will strip against the under faces of the standards 41 arranged to both sides of the knife, and this operation will effect a stripping of the substance from the knife, which accomplishes the result desired in this connection.

Finally although I may utilize a straight knife such as has been shown in Figures 1 to 3, which effects a transverse severance of the substance carried by the conveyor, I may conveniently employ a knife shown in Figures 5 and 6, in those instances where it is desired to not alone cut the substance transversely, but also longitudinally and edge-wise. With a view of effecting all of these cutting operations in the interval required for the knife to accomplish one depression, it will be seen, reference being had to the last named figures, that I may primarily secure a supplemental blade 44 to the main blade 45, and due to the fact that this blade extends transversely to the main blade 45, which latter corresponds to the blade 26, it will be obvious that the simultaneous longitudinal and transverse cutting of the substance will be effected. Racks 46 are attached to the head 37 and these racks upon being reciprocated by the head, serve to effect a rotation of gears 47, the teeth of which they engage. Thus secondary racks 130

48, which are mounted for slidable movement, and also engage the teeth of the gears 47, will be reciprocated in a plane parallel to the upper surface of the conveyor, and due to the fact that in the embodiment illustrated the knives 49, secured to the racks 48 are positioned in a plane substantially intermediate the plane occupied by the upper and lower faces of the substance to be cut, 10 this substance will also be divided horizontally into two slices of equal thickness.

Thus it will be appreciated that by the use of a cutting mechanism of the type shown in Figures 5 and 6 a depressing of the head 37 will result in the forming of 15 four separate blocks each of equal size, and the size of such a block as would be cut by the blade 26.

From the foregoing it will be appreciated 20 that all of the objects of this invention have been accomplished in that my improved type of cutting machine provides an extremely simple mechanical construction, consistent with the operations performed, and 25 these operations will at all times be positive in character, and an operator may be enabled to handle a great amount of work by the movement of a machine of this character. Thus the substance may be fed by any desirable means upon the forward end of the 30 table 11 and so upon the conveyor consisting of the plurality of platforms. This conveyor will serve to prevent any movement of the substance with respect to the same, 35 incident to the gripping shoes 16, associated with each platform, and the substance will be intermittently moved under the knife, which when the latter is of the type shown in Figures 1 to 3 effects a cutting of a single 40 block upon each depressing of the head. The substance will be fed in the form of a plurality of blocks to the rear end of the table, and thence by means of suitable mechanism such as the chute 30 and conveyor 31 45 upon the delivery table 32, whence it may be moved to any point desired. The platforms in the conveyor will now be moved through the bath provided by the trough 33, and subjected while in this bath to the action of the jets of fluid, thus thoroughly 50 cleaning all of the parts, and presenting the same in sanitary condition for the next cycle of operation.

It will be appreciated that numerous 55 modifications of structure and rearrangements of the machine parts may be resorted to without in the least departing from the scope of my claims; which are:

1. A cutting machine including a plurality of separately movable plate-like blades, 60 one of said blades being substantially T-shaped in cross-section to provide a T-shaped cutting edge, means for moving the last-mentioned blade to cut a brick of hard-frozen ice-cream, and means for moving the

other blade to cut said brick in a plane intersecting the plurality of cuts made by the blade of T-shaped cross-section.

2. In a cutting machine a plurality of blade-members two of which are movable 70 through cutting strokes in intersecting vertical planes and a third of which is movable in a horizontal plane intermediate the termini of the cutting strokes of the members first-mentioned, and means including an operative connection common to all the members for moving them in predeterminedly timed relation; said members being plate-like cutting members of materially greater width than thickness and mounted for edge-wise cutting movements and so adapted to shear hard-frozen ice-cream masses without dissimilar vibratory movements of different portions of any member.

3. A cutting machine including a first 85 blade, means for supporting and guiding said blade for movement in a vertical plane, a second blade, means for supporting and guiding the second blade for movement in a horizontal plane, means for thus moving said 90 blades, an operative connection between the two blade-moving means adapted to insure the movement of said blades in predeterminedly timed relation, and an operative connection associated with the first-mentioned connection and including an element 95 adapted to be driven by power means; said blades being plate-like cutting members of materially greater width than thickness and mounted for edge-wise cutting movements in 100 their supporting and guiding means, whereby, in combination with said power means, said blades are adapted to cut blocks of bone-hard ice-cream.

4. In a cutting machine, a plurality of 105 blades individually movable one in a vertical plane and the other in an intersecting horizontal plane, and means for moving said blades, said blades being true blades, that is, plate-like cutting members of materially 110 greater width than thickness and mounted for edge-wise cutting movement, whereby said blades are adapted, when said means for moving said blades are actuated by power means, to cut blocks of bone-hard ice- 115 cream.

5. In a cutting machine, a plurality of blades individually movable one in a vertical plane and the other in an intersecting horizontal plane, a conveyor for the substance to be cut by said blades, and means for moving said conveyor in a horizontal plane and for moving both blades; said 120 blades being true blades, that is, plate-like cutting members of materially greater width 125 than thickness and mounted for edge-wise cutting movement, whereby said blades are adapted, when said means for moving said blades are actuated by power means, to cut blocks of bone-hard ice-cream.

6. A cutting machine including a head, a blade attached to said head, means for reciprocating said blade, racks carried by said head, gears engaging said racks, secondary racks engaging said gears, and blades attached to said secondary racks.
7. A cutting machine including a head, a blade attached to said head, means for reciprocating said blade, racks carried by said head, gears engaging said racks, secondary racks engaging said gears, blades attached to said secondary racks, said latter blades working in a plane at right angles to the path of travel of said first named blade.
- 10 8. A cutting machine including a head, a blade attached to said head, means for reciprocating said blade, racks carried by said head, gears engaging said racks, secondary racks engaging said gears, blades attached to said secondary racks, said latter blades working in a plane at right angles to the path of travel of said first named blade.
- 15 9. A cutting machine including a head, a blade attached to said head, means for reciprocating said blade, racks carried by said head, gears engaging said racks, secondary racks engaging said gears, blades attached to said secondary racks, said latter blades working in a plane at right angles to the path of travel of said first named blade, and a further blade secured to said first named blade and extending at right angles to the same.

VINCENZO GUARDINO.
